UNITED STATES PATENT OFFICE

ALFRED MENDELL, OF GLENDALE, NEW YORK; ASSIGNOR TO MENDELL CANDIES, INC., OF BROOKLYN, NEW YORK, A CORPORATION OF NEW YORK

DISPLAY CARD

Application filed March 25, 1930. Serial No. 438,784.

This invention is an improvement in display and merchandising packages, and more particularly in a package for displaying stick like articles, such as the so called "suckers" or "pops", each including a lump of candy held on the end of a stick and a plurality thereof carried by a card of relatively stiff but flexible material to provide a convenient and attractive package as an article of commerce.

One of the primary objects of the invention is to provide a package including a card adapted to hold in display position a plurality of the "pops" in an attractive and striking position, the card being so shaped as to provide a handle for the assemblage.

Another object is to provide a package consisting of the card and the candies, adapted to be retailed as a package for a specified price.

Another object is the provision of a simple inexpensive card, which may be shaped flat, and assembled at the factory, and which when carrying the candy will lie in a container in a substantially flat position.

With these and other objects in view the invention consists in the construction and novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings forming a part hereof:—

Fig. 1 is a perspective view of the improved card.

Fig. 2 is a rear view.

Fig. 3 is a section on the line 3—3 of Fig. 2.

In the present embodiment of the invention, the improvement comprises a card 1 of relatively stiff but flexible material and of suitable size and shape, having near each end a row of openings 2 and 3, respectively. The rows are spaced apart from each other, and the openings of each row correspond in number, and in relative position in the row to those of the other row.

As for instance in the present case three

openings are provided in each row, the rows being parallel, and the openings are so arranged, that upon flexing or bowing the card the sticklike article may be passed through a pair of corresponding openings in the rows. It will be apparent from an inspection of Fig. 2, that the openings 3 are spaced closer than the openings 2, but the relative positions of the openings in the rows is the same.

The improved card in the instance shown is of least width intermediate its ends, and nearer one end than the other, and from the line of least width, the card gradually increases in width toward each end. The angle of increase is the same at each side of the line of least width, so that when the card is bent upon said line of least width, the side edges of the two parts will be in register. The card may be creased transversely at the line of least width to facilitate bending, and for convenience the line of least width is hereafter designated as the crease, it being understood, however, that a crease is not necessary. That portion 5 of the card outside the line of least width or crease is adapted to be bent backward to lie in rear of the card body, as shown in Fig. 3.

When so bent, the openings 3 may be brought into axial alinement with the openings 2, as clearly shown in Fig. 2, so that each pair of alined openings in the two rows may receive a stick-like article, as for instance the stick 6, of a "sucker" or "pop". Each stick carries a lump or mass 7 of candy, and the mass is wrapped, as shown at 8, the wrapping extending some little distance down upon the stick as shown at 9.

The openings 2 are somewhat larger in diameter than the openings 3, so that the wrapping on the stick may be passed through the openings 2. In placing the sticks, the card is flexed or bowed transversely and the portion 5 is bent as shown in Fig. 3, and the stick is passed down through an opening 2, from front to rear, and through an opening 3, also from what is the front of the card before bending of the portion 5. The free end of the stick lies between the body at the rear face of the card and the portion 5, as shown so that the major portion of the stick is con-

cealed at the rear face of the card and substantially the entire front face of the card is unobstructed.

In order to place the sticks, the end of the card remote from the crease is also flexed or bent backward, as shown in Figs. 1 and 3, and this arrangement insures that when a stick is pulled outwardly, in the attempt to dislodge it from the card, the bent ends of the card will move with the stick for a certain distance and will exert stress on the stick to brake the withdrawing movement thereof. This is assisted also by the wrapping 9, and thus the "pops" will not readily fall out when the card is inverted.

Preferably the openings 2 and 3 are so arranged as to hold the articles in a relation diverging from the crease, and the side edges of the card are shaped to be substantially parallel with the outermost sticks. From this results that the side edges of the card diverge from the crease in each direction, the side edges of the portion 5 being in substantial register with the side edges of the card body. Suitable display matter or advertising matter may be arranged upon the unobstructed front face of the card, as indicated at 10.

It will be apparent from the drawing that the improved card is substantially fan shaped, and while providing in combination with the candies an attractive display, it may be used after the removal of the candies, as a fan by the children who buy the candies.

35 What is claimed as new is:—

1. As a new article of commerce, a "lolly pop" sales package comprising a card of relatively stiff but flexible material having a row of openings at opposite ends thereof and the lower end folded rearwardly and upwardly to bring its row of openings at the rear of the card, and "stick" confections of the lolly pop type carried by said card, the sticks of the confections extending through the aligned openings at opposite ends of the card in such a manner as to flex or bow the card transversely and through its inherent resiliency exert a gripping stress upon the sticks, the candy portion of each stick being disposed in a line on the front face of the card near the upper edge thereof, and the sticks being disposed at the rear face of the card.

2. A display package of candies of the "sucker" type comprising a card of relatively stiff but flexible material and a plurality of "stick" confections of the sucker type carried thereby, said card having a transverse row of openings near each end, the openings of each row corresponding in number and relative position to those of the other row and so arranged that when the card is folded intermediate its ends on a transverse line the corresponding openings of the rows will be brought into alignment to enable the stick portion of the confections to be thrust

through each pair of openings with one end of the stick confined between the folded portions and the confection carrying end located at the front face of the package, the said card having such inherent resiliency as to exert a gripping action on the sticks.

3. A display package of candies of the "sucker" type comprising a substantially fan-shaped card of relatively stiff but flexible material, and a plurality of "stick" confections of the sucker type carried thereby, said card having a plurality of spaced openings arranged transversely thereof near each end and the lower end of the card being folded rearwardly and upwardly to dispose its row of openings at the rear face of the card, the sticks of the confections extending through pairs of aligned openings longitudinally of the card so as to flex the latter transversely and through its inherent resiliency exert a gripping action on the sticks, the confection portion of each stick being disposed at the front of the card and the sticks at the rear, the said openings at the opposite ends of the card being spaced relatively to each other in such a manner as to display the confections in a fan-like formation.

4. As a new article of commerce, a "lolly pop" sales package, comprising a substantially fan-shaped card of relatively stiff but flexible material, and a plurality of stick confections of the "sucker" type carried thereby, said card having a row of spaced openings near each end thereof, and the lower end of the card being folded rearwardly and upwardly to dispose its row of openings at the rear face of the card, the sticks of the confections extending through the aligned openings at the opposite ends of the card in such a manner as to flex the card transversely and exert a gripping stress upon the sticks, the candy portion of each stick being disposed in fan-like formation at the front face of the card near its wider end and the sticks being disposed at the rear face of the card, the remaining front face of the card being unobstructed and adapted to have imprinted thereon appropriate advertising matter.

Signed at Brooklyn in the county of Kings and State of New York this 22nd day of March, A. D. 1930.

ALFRED MENDELL.
